TURNER C. PURINGTON, OF LINCOLN, ASSIGNOR TO HIMSELF AND ANTOINE MAYOUX, OF MARYSVILLE, CALIFORNIA.

Letters Patent No. 97,314, dated November 30, 1869.

IMPROVED CHAIR-SPRING.

The Schedule referred to in these Letters Patent and making part of the same.

To all whom it may concern:

Be it known that I, TURNER C. PURINGTON, of Lincoln, in the county of Placer, and State of California, have invented a certain new and improved Chair-Spring; and I do hereby declare that the following is a full and exact description of the same, reference being had to the accompanying drawings, and to the letters of reference marked thereon.

My invention relates to a certain improvement in attaching the ordinary spiral springs to the two front legs of a chair, whereby rockers are entirely dispensed with.

In the drawings—

Figure 1 is an elevation of the spring, with one leg in position in the nut or step.

Figure 2 is a bottom view.

Figure 3 is a vertical section of nut.

The nut A is made of metal, and is provided with a screw-thread, B, so that it can be screwed to the leg of an ordinary chair, and instead of weakening and splitting the leg, as in case where a hole is bored and a screw inserted to hold and attach the step, my mode of attaching the nut or step serves to strengthen it.

The nut can also be easily and quickly removed, and the chair be made to assume the ordinary position again, standing on four legs.

The ease and convenience in applying the spring to the nut will be readily seen and appreciated. With this end in view, I provide the top of the nut with a collar or shoulder, C, and make a half oval spiral or incline groove, D, around the outer surface of the nut, commencing at the base, so that by inserting the small end of the spiral spring E in the groove, and turning it around, the top coil of the spring will rest firmly in the upper part of the groove, under the shoulder or lip of the nut, and thus prevent doubling or oscillating from side to side, and the chair will resume all the soft and yielding-motion imparted to it by the bearing down of the springs.

Having thus described my invention, What I claim, and desire to secure by Letters Patent, is—

In combination with the spiral spring, the nut A, provided with an inner screw-thread, B, outer incline-groove D, and shoulder C, substantially as and for the purpose set forth.

In witness whereof, I have hereunto set my hand and seal.

TURNER C. PURINGTON. [L. S.]
